UNITED STATES PATENT OFFICE.

CHARLES C. FRAUTZ AND HAROLD F. PENNEY, OF GENEVA, NEW YORK, ASSIGNEES TO PHILLIPS & CLARK STOVE CO. INC., OF GENEVA, NEW YORK, A CORPORATION OF NEW YORK.

CLEAN-OUT FRAME AND CAP THEREFOR.

Application filed March 19, 1923. Serial No. 625,963.

To all whom it may concern:

Be it known that we, CHARLES CLARK FRAUTZ and HAROLD F. PENNEY, citizens of the United States, residing at Geneva, in the 5 county of Ontario and State of New York, have invented certain new and useful Improvements in Clean-Out Frames and Caps Therefor, of which the following is a specification.

10 The object of this invention is to provide the clean out opening of a hot air furnace with a new and improved type of frame and cap with which this opening can be sealed so that the gases from the fire cannot escape 15 into the hot air risers of the furnace.

Another object of this invention is to so construct this frame and cap that the cap will not corrode as is the case with sheet metal caps, but can readily be removed from 20 the clean out opening and put back in place again without injury to the cap.

These and other objects of this invention will be fully illustrated in the drawings, described in the specification and pointed out 25 in the claims at the end thereof.

In the accompanying drawings:

Figure 1 is a front elevation of the clean out frame and cap.

Figure 2 is a view partly in section of the 30 clean out frame and cap, the section being taken on the line 2^x—2^x of Figure 1.

Figure 3 is a perspective view of the clean out frame and cap as they will appear when viewed from the rear and partly separated.

35 Figure 4 is a detail perspective view of a section of a radiator of a hot air furnace showing the clean out opening to which the clean out frame is mounted ready to have the cap attached thereto.

40 Figure 5 is a vertical sectional view of a hot air furnace having the clean out frame and cap attached to the radiator thereof.

In the several figures of the drawings like reference numerals indicate like parts.

45 Hot air furnaces are usually built with a radiator having a clean out opening and the practice is to provide this opening with a sheet metal cap that is slipped over the opening to prevent the gases or products of combustion from escaping into the risers of the 50 furnace. These sheet metal caps are ex-

posed to the action of the gases or products of combustion and after a period of time they corrode due to this exposure. In removing such a cap for the purpose of cleaning 55 out the soot collected in the radiator, it is usually broken or badly bent due to its corroded condition and weakened so that a new cap must be provided in its place. Furthermore the sheet metal caps used in present 60 day construction are usually found to be leaky and allow some of the gases or products of combustion to escape into the risers.

In the clean out frame and cap forming the subject matter of our present invention 65 the parts are so constructed that they form a perfect seal for the clean out opening of the radiator. The parts are made out of cast iron and will resist the action of the 70 gases as well as any other part of the furnace that is exposed to them.

As illustrated in the drawing, the clean out frame is attached to the end of the clean out duct 1 of the hot air radiator 2 of a furnace, and comprises a cast iron ring 3 having a short sleeve extension 4 of enlarged diameter formed at the back thereof. At the top of this sleeve extension 4 is formed the boss 5 having a threaded opening 6 provided therein into which a suitable set screw 75 7 may be threaded to clamp the upper end of the sleeve 4 of the clean out frame in place on the outer end of the clean out duct 1. For this purpose the short sleeve extension 4 is made with an inside diameter 80 slightly larger than the outside diameter of the clean out duct 1 of the radiator so that the sleeve can be readily slipped over this duct and be clamped in place thereon by 85 means of the set screw 7.

The bottom of the clean out frame is anchored to the top of the shell 8 surrounding the feed door opening of the combustion dome and leading to the fire pot, all constituting part of the shell of the furnace. For this purpose a pair of sliding brackets 9 and 10 are provided. Of these brackets, the bracket indicated by reference numeral 9 is clamped to the under side of the pocket 11 formed in the short sleeve extension 4 of the 100 clean out frame as indicated in Figures 1, 2 and 3. This pocket is adapted to hold either

the nut or head of the clamping bolt 12 that is inserted into the slot 13 in the bottom of the pocket 11. The clamping bolt 12 passes through the flange 14 formed at the top of 5 the bracket 9 and is adapted to clamp this flange and with it the bracket 9 in place on the underside of the clean out frame.

The bracket 10 in turn is clamped to the shell 8 as indicated in Figures 4 and 5, a 10 suitable bolt hole being provided in this shell into which the bolt 15 may be threaded or otherwise fastened to clamp the flange 16 of the bracket 10 rigidly to the top of the shell 8. A sliding adjustment between the 15 two brackets 9 and 10 takes care of variations in the dimension between the top of the shell 8 and the bottom of the clean out frame. This adjustment is made possible by the slot 17 provided in the bracket 9. The 20 bolt 18 carried in the bracket 10 passes through this slot and can slide up or down therein so that it can be fastened to hold the two brackets in the desired position with relation to each other.

25 On the inside of the ring 3 of the clean out frame at two diametrically opposite points are provided a pair of cam lugs 20 and 21. The cam surface of these lugs faces the rear of the clean out frame and the dogs 30 22 and 23 of the cap 24 are adapted to engage this cam surface. As illustrated, the cap 24 comprises a slightly dished shell having the dogs 22 and 23 projecting rearwardly from it at diametrically opposite points on 35 the rear of the shell. The rear edge 25 of the cap 24 when placed against the front of the clean out frame makes contact with the front edge 26 of the clean out frame and by giving the cap a turn so as to make the dogs 22 and 40 23 engage the rear or cam surface of the cams 20 and 21 and slide up thereon, the two edges are tightly drawn against each other and form a gas tight joint between them. For this reason the outer surface of the two 45 edges 25 and 26 are finished to provide smooth surfaces that can be tightly clamped together.

The cap 24 is turned to be locked to the frame as above pointed out by means of the 50 same crank handle that is used to turn the grate bars of the furnace. This handle is slipped over the triangular lug 27 provided on the outside of the cap 24 in the manner in which it is slipped over the end or ends of 55 the grate bars. A short turn of the handle thus turns the cap and locates its dogs 22 and 23 at the rear of the lugs 20 and 21 so that a further rotation makes the hook shaped ends of the dogs ride up on the cam 60 surfaces of the lugs 20 and 21 which operate to draw the edge of the cap against the edge of the frame until the two edges are tightly clamped together.

In the outer shell of the furnace the door 65 28 is placed in front of the cap 24 which

conceals it but provides a place through which the cap can be removed when the radiator is to be cleaned out.

We claim:

1. In a clean out frame and cap therefor 70 for furnaces, the combination of a furnace shell, a ring adapted to be placed in front of the clean out duct of the radiator of said furnace shell, a pair of brackets, one of said brackets being anchored to the bottom of 75 said ring and the other of said brackets being anchored to said furnace shell, means for adjustably clamping the free ends of said pair of brackets together to hold said ring in place on the end of said clean out 80 duct, a cap for said ring and means for clamping said cap to said ring.

2. In a clean out frame and cap therefor 85 for furnaces, the combination of a furnace shell, a ring, a sleeve extension at the rear of said ring, a pair of cam lugs located at diametrically opposite points within said ring, a cap, a pair of dogs located at diametrically opposite points at the back of said 90 cap, said cap being adapted to be placed against said ring and turned to engage said dogs behind said cam lugs and draw said cap against said ring to close the opening formed by said ring, a pocket formed in the bottom of said sleeve extension, a bolt 95 adapted to be anchored in said pocket, a bracket fastened to the under side of said sleeve extension by means of said bolt, a second bracket being adjustably clamped to said first bracket said second bracket being 100 anchored to the shell of the furnace.

3. In a clean out frame and cap therefor 105 for furnaces, the combination of a furnace shell having a clean out duct, a ring, a sleeve extension at the rear of said ring, a pair of cam lugs located at diametrically opposite points within said ring, a cap, a pair of dogs located at diametrically opposite points at the back of said cap, said cap being adapted 110 to be placed against said ring and turned to engage said dogs behind said cam lugs and draw said cap against said ring to close the opening formed by said ring, a pocket formed in the bottom of said sleeve extension, a bolt adapted to be anchored in said 115 pocket, a bracket fastened to the under side of said sleeve extension by means of said bolt, a second bracket being adjustably clamped to said first bracket said second bracket being anchored to the shell of the furnace, means for clamping the top of said sleeve extension to the end of the clean out 120 duct of the furnace shell.

4. In a clean out frame and cap therefor 125 for furnaces the combination of a furnace shell having a clean out duct, a ring adapted to be placed against the end of said clean out duct, a pocket formed on the periphery of said ring, a bolt anchored in said pocket, a bracket clamped to said ring by said bolt, 130

said bracket holding said ring on said clean out duct with relation to said furnace shell.

5. In a clean out frame and cap therefor for furnaces the combination of a furnace shell having a clean out duct, a ring, a cap adapted to close the opening in said ring, said ring being adapted to telescope over the end of said clean out duct, a set screw threaded into the periphery and projecting 10 through said ring to engage the clean out duct and clamp said ring to said clean out

duct, a pocket formed on the inside of said ring, a bolt anchored in said pocket, a bracket adapted to be clamped to the outside of said ring by means of said bolt, said bracket connecting said ring to said furnace shell, means for increasing or decreasing the length of said bracket. 15

In testimony whereof we affix our signatures.

CHARLES C. FRAUTZ.
HAROLD F. PENNEY.
